ROBERT TURNER, OF NEW YORK, AND BENJAMIN R. CORLEY, OF BROOKLYN, NEW YORK.

PLATE-PRESS ATTACHMENT.

SPECIFICATION forming part of Letters Patent No. 719,909, dated February 3, 1903.

Application filed July 25, 1902. Serial No. 116,929. (No model.)

To all whom it may concern:

Be it known that we, ROBERT TURNER, a subject of the King of Great Britain, and a resident of the city of New York, borough of

5 Manhattan, in the county of New York, and BENJAMIN R. CORLEY, a citizen of the United States, and a resident of the city of New York, borough of Brooklyn, in the county of Kings, State of New York, have invented a new and

10 Improved Plate-Press Attachment, of which the following is a full, clear, and exact description.

The invention relates to copper and steel plate printing; and its object is to provide a new and improved plate-press attachment which is simple and durable in construction, very effective in operation, and arranged to automatically stop the plate-press after each impression.

15 The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a plan view of the improvement, 20 parts being broken out. Fig. 2 is a longitudinal sectional elevation of the same on the line 2 2 of Fig. 1. Fig. 3 is a sectional side elevation of the tripping-lever and cam in a tripping position; and Fig. 4 is an end elevation of the same, showing the tripping-lever in a retaining position.

The plate-press on which the improvement is applied is of usual construction and mounted on a frame A, in which is journaled a 25 impression-roller B, operating in conjunction with a bed or table C, mounted to travel longitudinally on friction-rollers C' and receiving an initial forward movement by an arm D on the impression-roller B engaging a cam E on the said table C. The return movement of the latter is accomplished by the usual weight F, (see Fig. 2,) and the underside of the said bed or table travels over a pressure-resisting roller G, located in vertical alinement with 30 the impression-roller B.

On the rear portion of the main frame A is journaled a driving-shaft H, provided with a pulley H', connected by a belt with other machinery for imparting a continuous rotary motion to the said shaft H. On the shaft H 55 is secured a clutch member I, adapted to be engaged by a clutch member I', mounted to turn loosely and to slide lengthwise on the shaft H, and on the said movable clutch member I' is secured or formed a sprocket-wheel 60 J, over which passes a sprocket-chain J', also passing over a sprocket-wheel J'', secured on the shaft B' of the impression-roller B. The movable clutch member I' is engaged by a shifting-lever K, fulcrumed on the main 65 frame and pressed on by a spring L to normally hold the shifting-lever K in such a position that the movable clutch member I' is out of mesh with the clutch member I.

On the under side of the shifting-lever K 70 is fulcrumed a tripping-lever N, pressed on by a spring O to hold the end N' of the said tripping-lever in an uppermost position, as shown in Fig. 2, the said end N' extending through an opening K' in the shifting-lever 75 K, as plainly indicated in Fig. 3.

The end N' of the tripping-lever N is adapted to be engaged by a cam P, secured on the impression-roller shaft B', adjacent to the sprocket-wheel J'', as plainly indicated in the 80 drawings. The cam P is provided with an annular flange P', on the outer face of which is secured a cam-face P'', adapted to engage the end N' of the tripping-lever N, so as to press the same downward against the tension 85 of the spring O to finally bring the top of the end N' to the outer portion of the said cam-face P'', which outer portion is in transverse alinement with the peripheral face of the flange P' to allow the spring L to swing the 90 lever K automatically into an inactive position, as indicated in dotted lines in Fig. 1. It is understood that when this takes place the movable clutch member I' is moved out of engagement with the clutch member I. 95

The operation is as follows: When the plate to be printed from is in position on the bed C and it is desired to make an impression, then the operator takes hold of the shifting-lever K and presses the outer end of the 100

tripping-lever N, so that the end N' is flush at its top surface with the top of the lever K, and then the operator imparts an outward swinging movement to the lever K, so that 5 the clutch member I' is moved in engagement with the clutch member I, and consequently the rotary motion of the shaft H is transmitted by the sprocket-wheels J and J² and sprocket-chain J' to the impression-roller B 10 to rotate the latter and to cause an impression to be made in the usual manner, it being understood that the bed C is started on its forward movement by the action of the arm D on the cam E. As soon as the roller B has started to turn the operator releases the 15 tripping-lever N, so that the spring O thereof imparts a swinging motion to the tripping-lever to cause the end N' to pass up and engage the outer face of the flange P' of 20 the cam P, rotating with the impression-roller B in the direction of the arrow a'. (See Fig. 2.) The operator now releases the lever K, and as soon as the impression-roller B has nearly completed one revolution then the 25 cam-face P² engages the end N' of the tripping-lever N and imparts a swinging motion thereto against the tension of the spring O until the end N' reaches the outer portion of the cam-face P² in alignment with the per- 30 ipheral surface of the flange P', so that the spring L now imparts a return swinging motion to the lever K, and the latter now shifts the clutch member I' outwardly and out of engagement with the clutch member I, and 35 consequently the sprocket-wheels J and J², sprocket-chain J', impression-roller B, and cam P come automatically to a stop, with the impression-roller B again in a starting position for the next impression. The bed C also 40 returns in the usual manner by the action of the weight F.

For making a second impression the above-described operation is repeated—that is, the operator swings the shifting-lever K outward, 45 with the tripping-lever N having its end N' in a lowermost position, so as to clear the flange P' of the cam P, and the operator holds the lever K long enough in this position until the roller B is started and the cam- 50 face P² has left its lowermost position and about reached the position shown in Fig. 2. The operator then releases the tripping-lever N, which now engages with its end N' the outer face of the flange P' to lock the shifting-lever K temporarily in position, with the clutch member I' held in mesh with the clutch member I.

From the foregoing it will be seen that the impression-roller B automatically stops in 60 starting position after each impression, and the impression-roller can only be started again by the operator manipulating the lever K and tripping-lever N, as previously explained.

Having thus described our invention, we 65 claim as new and desire to secure by Letters Patent—

1. A plate-press having a driving-gear for

an impression-roller, and a device controlled automatically from the impression-roller, to stop the driving-gear after each impression, 70 the said device consisting of a cam on the shaft of the impression-roller, a clutch on the drive-shaft, and two substantially horizontal levers, one working in a horizontal plane and operating the clutch and the other working in 75 a vertical plane and acted upon by the cam and both being manually controlled for starting the driving-gear, as set forth.

2. A plate-press attachment comprising a 80 driving-shaft, a gearing for driving an impression-roller from the said driving-shaft, a clutch for connecting the driving-shaft with the said gearing, and a shifting device controlled from the impression-roller of the plate-press for throwing the clutch out of gear after 85 each impression, as set forth.

3. A plate-press attachment comprising a 90 driving-shaft, a gearing for driving an impression-roller from the said driving-shaft, a clutch for connecting the driving-shaft with the said gearing, and a shifting device controlled from the impression-roller of the plate-press for throwing the clutch out of gear after 95 each impression, the said shifting device comprising a spring-pressed shifting-lever for the clutch, a retainer on the said lever and a cam revolving in unison with the impression-roller and adapted to be engaged by the said retainer, as set forth.

4. A plate-press attachment comprising a 100 driving-shaft, a gearing for driving an impression-roller from the said driving-shaft, a clutch for connecting the driving-shaft with the said gearing, and a shifting device controlled from the impression-roller of the plate-press, for throwing the clutch out of gear 105 after each impression, the said shifting device comprising a spring-pressed shifting-lever for the clutch, a spring-pressed tripping-lever fulcrumed on the said shifting-lever and 110 a cam revolving in unison with the impression-roller and adapted to be engaged by the free end of the said tripping-lever, as set forth.

5. A plate-press attachment comprising a 115 driving-shaft, a gearing for driving an impression-roller from the said driving-shaft, a clutch for connecting the driving-shaft with the said gearing, and a shifting device controlled from the impression-roller of the plate-press, for throwing the clutch out of gear 120 after each impression, the said shifting device comprising a spring-pressed shifting-lever for the clutch, a spring-pressed tripping-lever fulcrumed on the said shifting-lever, and a cam revolving in unison with the impression-roller and adapted to be engaged by the 125 free end of the said tripping-lever, the said cam having an annular flange and a cam-face on the outer side thereof, as set forth.

6. A plate-press having a cam revolving in 130 unison with an impression-roller, a gearing for driving the impression-roller, a clutch for connecting and disconnecting the gearing and the driving-shaft, a spring-pressed shifting-

lever operating the clutch, and a second spring-pressed locking-lever operating in a plane at right angles to that of the shifting-lever and acted upon by said cam, and means for retaining the locking-lever in the plane of the cam for a definite period, substantially as described.

5 In testimony whereof we have signed our

names to this specification in the presence of two subscribing witnesses.
